UNITED STATES PATENT OFFICE

111,525

DESIGN FOR A MOTOR-SCOOTER

David C. Rockola, Chicago, Ill., assignor to Rock-Ola Manufacturing Corporation, Chicago, Ill., a corporation of Delaware

Application June 6, 1938, Serial No. 77,620

Term of patent 14 years

To all whom it may concern:

Be it known that I, David C. Rockola, a citizen of the Dominion of Canada and a resident of Chicago, in the county of Cook and State of Illinois, have invented a new, original, and ornamental Design for a Motor-Scooter, of which the following is a specification, reference being had to the accompanying drawings, forming a part thereof.

In the drawings:

Fig. 1 is a perspective view taken from one side of a motor-scooter showing my new design;

Fig. 2 is a perspective view taken from one side and forwardly of the motor-scooter; and

Fig. 3 is a perspective view taken from one side and rearwardly of the motor-scooter, the handle bars in this view being broken away.

The dominant features of my new design have been indicated in solid lines in the drawings.

I claim:

The ornamental design for a motor-scooter, substantially as shown and described.

DAVID C. ROCKOLA.
